UNITED STATES PATENT OFFICE.

EDWIN S. VOTEY, OF SUMMIT, NEW JERSEY, ASSIGNOR TO AEOLIAN COMPANY, OF NEW YORK, N. Y., A CORPORATION OF CONNECTICUT.

RECORDING DEVICE.

1,076,338.

Specification of Letters Patent.

Patented Oct. 21, 1913.

Application filed March 14, 1912. Serial No. 683,692.

To all whom it may concern:

Be it known that I, EDWIN S. VOTEY, a citizen of the United States, and a resident of Summit, in the county of Union and State 5 of New Jersey, have invented certain new and useful Improvements in Recording Devices, of which the following is a specification.

This invention relates to new and useful 10 improvements in recording devices and the object of my invention is to provide a new and improved device of this kind for automatically recording, in the form of perforations and slots cut in a strip of paper, correct representations of the sound produced 15 in playing a piano while accompanying a musical production produced on a phonograph or talking machine or otherwise, in exact accordance with the time, that is, the duration of and the intervals between the 20 notes, so that the record thus produced can be used in a properly adjusted piano player for accompanying a phonograph or a talking machine.

25 In the accompanying drawings in which like letters of reference indicate like parts in all the figures: Figure 1 is a diagrammatic elevation of my new and improved recording machine. Fig. 2 is a diagrammatic side 30 view of the same, parts of the piano being shown.

The record sheet 1, into which the record of the piano playing is to be cut, is unrolled from the spool 2 and upon the spool 3, and 35 passed over the slightly beveled or curved top of a die plate 4 in the same manner that such a sheet is passed over the tracker board in a player piano or playing attachment the movement of the sheet being a continuous 40 one and at the same speed throughout. The spool 3 on which the sheet is wound is driven by conventional gearing 4' such as is commonly used in playing attachments and this gearing is driven by means of a sprocket 45 chain 5 from a sprocket wheel 6 on a shaft 7 driven by a pneumatic motor 8 such as commonly used in playing attachments and the air is exhausted from this motor 8 through a regulating bellows 9 into the air pumping 50 mechanism 10 driven by a belt 11 and pulleys from an electric motor 12 or other suitable source of power. By means of a bevel cog wheel 13 on the shaft 7 the bevel cog wheel 14 is rotated and by means of a clutch 55 15 of conventional construction, having a

suitable adjusting handle 16, the shaft 17 supporting a rotative talking machine disk support 18 can be rotated from said cog wheel 14 and thus the phonograph disk 19 can be rotated at such speed of rotation as 60 to coincide with the speed of the longitudinal movements of the sheet of paper on which the piano record is being cut.

The talking machine diaphragm 20, connected with the stylus in conventional manner is connected with ear pieces 22 such as are commonly used on talking machines when a horn is not desired and the sound is to be conveyed directly to the ear of the 70 listener.

For each key of a pianoforte, the notes of which are to be recorded a suitably guided vertically reciprocating punch 23 is provided above the die plate 4 there being a corresponding opening in the die plate for each reciprocating punch 23 and each punch 23 is pivotally connected with the pivoted armature 24 of an electromagnet 25, which electromagnet has one terminal connected by a conductor 26 with one terminal of a 80 battery 27, the other terminal of the electromagnet 25 being connected by a conductor 28 with one terminal of an electric interrupter or make and break apparatus 29 of any suitable construction, the other terminal of which is connected by a conductor 30 with a contact piece 31 located beneath the free end of a steel spring 32 attached to the piano frame beneath each key 33 and which spring 32 is connected by a conductor 34 with that terminal of the battery 27 opposite the one with which the conductor 26 is connected. Whenever a key 33 is depressed sufficiently to cause the striking of the corresponding hammer and to hold the corresponding damper off its string, the descending part of the key presses the corresponding contact spring 32 against the contact 31 whereby the electric circuit through the battery 27, the corresponding make and break apparatus 29 and corresponding electromagnet is closed. As long as this circuit remains closed by the depressing of the key the armature 24 is vibrated with great rapidity and the corresponding punch pin 23 is 105 forced with corresponding rapidity through the moving paper sheet 1, into the corresponding die aperture, thus making a perforation or slot corresponding to the length of time that the key remains depressed suffi- 110

ciently to keep the circuit closed in the manner described. As soon as the circuit is broken by the removal of the pressure upon the piano key, the spring 36 acting on the armature 24 keeps the corresponding punch pin raised, thus permitting the paper to be moved lengthwise under said punch pin without any action of the punch pin upon the paper. Accordingly as the keys of the piano remain depressed for a greater or less length of time, perforations or slots of greater or less length are cut by the punches in the sheet 1 corresponding to the notes relating to the keys depressed and when said punches are raised the paper will be moved to form blank spaces or bridges between the successive perforations of each longitudinal row, said blanks or bridges corresponding in length to the time intervals between the successive soundings of the same note.

It is to be understood that the paper and the phonograph record disk 19 are moved by the motor at the same ratio of speed throughout.

The operator or player inserts an ear piece 22 in his ears and as he hears the sounds produced by the phonograph record he plays the accompaniment upon the piano either manually or by means of a playing attachment and as this accompaniment is being played a perfect and correct record of the same is cut into the sheet 1 which may be subsequently used as a master sheet for making copies of the same or which may be used as an original for playing the accom-

paniment to the piece on the phonograph or talking-machine record used or a copy of the same.

Having described my invention what I claim as new and desire to secure by Letters Patent is:—

In a note recording machine the combination with a means for feeding a sheet of paper uninterruptedly, of a die plate over which said sheet is passed, punches coöperating with the die plate to perforate the sheet of paper passed over the die plate, an independent and individual electric means for operating each punch, an electric current interrupter for each individual electric punch operating device, an electric circuit closing device pertaining to each key of a key musical instrument, a source of electricity, an electric connection from said circuit closing device to the corresponding current interrupter, an electric connection from said current interrupter to the corresponding electric punch operating device, an electric conductor from the electric punch operating device to the source of electricity, and a conductor extending from the source of electricity to the circuit closing device pertaining to the key, substantially as set forth.

Signed at New York city, in the county of New York and State of New York this 17 day of Jany. A. D. 1912.

EDWIN S. VOTEY.
